UNITED STATES PATENT OFFICE.

SAMUEL THEODORE BITTENBENDER, OF BROOKLINE, AND JOHN G. ALLAN, OF QUINCY, MASSACHUSETTS.

HEAT-TREATING FURNACE.

Application filed August 30, 1921. Serial No. 496,830.

To all whom it may concern:

Be it known that we, SAMUEL THEODORE BITTENBENDER and JOHN G. ALLAN, citizens of the United States, residing, respectively, 5 at Brookline, in the county of Norfolk and State of Massachusetts, and at Quincy, in the county of Norfolk and State of Massachusetts, have invented a new and useful Improvement in Heat-Treating Furnaces, of 10 which the following is a specification, like reference characters on the drawings indicating like parts in the several figures.

This invention relates to furnaces designed especially for use in tempering, annealing, 15 or otherwise heat treating metal bars or parts.

It is an important object of the invention to devise a furnace of this character in which the parts to be treated can be inserted in the 20 furnace and removed therefrom more conveniently than in the usual types of furnaces. The invention also aims to devise a furnace construction which can be manufactured economically, which will be economical of 25 fuel, will be adapted to manufacture in a variety of sizes, and which generally will meet the practical requirements of a furnace of this character.

The nature of the invention will be readily 30 understood from the following description when read in connection with the accompanying drawings, and the novel features will be particularly pointed out in the appended claims.

35 Referring now to the drawings,

Figure 1 is a front elevation, partly in cross section, of a furnace embodying the present invention;

Fig. 2 is an end view of the furnace shown 40 in Fig. 1;

Fig. 3 is a vertical cross sectional view of the furnace shown in Figs. 1 and 2; and

Fig. 4 is a vertical, longitudinal, cross-sectional view of a portion of the furnace, taken 45 on the line 4—4, Fig. 3.

The construction shown comprises a lower section 2 and an upper section or arch 3. These parts may be of any suitable dimensions, but usually the length of a furnace of 50 this character is great compared to its diameter, particularly when it is to be used for the treatment of bars, rods, and the like.

While the furnace may be of any suitable shape, we prefer to make it in a substantially cylindrical form, as shown, and to divide this cylinder on a substantially horizontal plane located below the axis of the cylinder. Each section, as shown, consists of a metal shell 4 reinforced by bars 5 of angular cross section. These metal shells have a 60 refractory lining which may consist of fire brick 7, the surface and joints of the brick being covered by a fireproof cement 8, such as that commonly used in this trade.

A hearth 10, also made of fire brick, or other refractory material, is supported horizontally in the lower section 2, this hearth resting on fire brick partitions 11. The space below the hearth forms a combustion chamber which is divided by the partitions 70 11 into compartments 12. The gas or other fuel to be burned is led into these compartments by pipes 13, these pipes leading from a supply pipe or manifold 14 to which the fuel mixture is supplied in any suitable manner. The gas burns in the compartments 12 of the combustion chamber and the gaseous products of combustion flow upwardly, through a space 15 provided at the back of the hearth, into the heating chamber 29. 80 These gases then flow over the hearth and circulate throughout the chamber; the products of combustion venting at the ends as indicated by the arrows in Fig. 1. The hearth 10 is not as long as the lower section 2 so 85 that spaces are provided at the opposite ends of the hearth through which these gases may flow downwardly into flues 16—16 that lead from the opposite ends of the lower section 2. 90

The lower section of the furnace is supported on brackets 18 spaced at suitable intervals longitudinally of the furnace and thus is normally stationary. The upper section 3, however, is mounted to swing about a 95 horizontal axis located at the back of the furnace and substantially on a level with the upper surface of the hearth. For this purpose a series of small brackets 19 are secured to the rearward side of the upper section 100 each having a cylindrical surface to fit into a semi-cylindrical socket formed in a bracket 20 that is secured to the lower section 2.

Any convenient mechanism may be provided for raising and lowering the upper section or arch 3, the construction shown consisting of two ropes or cables 21-21 secured to the front of the arch and wound several times about a shaft 22 which is supported in bearings mounted on a frame 23 that overhangs the furnace. Each of these cables runs over a pulley 24 at the back of the frame and supports a counter-weight 25. A crank 26 is secured to the end of the shaft 22 and affords a convenient means for turning this shaft to raise or lower the front of the arch 3.

15 It will now be appreciated that by raising the arch or upper section 3, the furnace will be opened for its entire length, thus facilitating the placing and arranging of articles to be heat treated on the hearth 10 and their 20 subsequent removal therefrom. These operations are further facilitated by placing the hearth on the same level with the front edge of the lower section of the furnace so that the heated articles may be rolled or 25 placed on to and taken off the hearth and out of the furnace with relatively little effort. A further advantage of this construction is that it is very economical of fuel, due especially to the compact arrangement of the parts. It will also be evident 30 that this furnace can be constructed economically and that it lends itself conveniently to designs in either large or small units.

35 In order to enable the attendant to observe the progress of the heating operation and the condition of the materials being treated, a series of observation openings 27 are provided in the front of the arch, each of these 40 openings normally being closed by a plug 28 of clay, fire brick or other suitable material.

While we have shown and described a furnace in which the arch is made as a unit, 45 the arch may be made in two or more sections which can be raised and lowered separately or together. If a furnace embodying our invention is made of substantial length the making of the arch in sections 50 may be advisable in order better to take care of contraction and expansion. Again under certain conditions it might prove advisable to divide the metal shell 4 transversely into sections, leaving the refractory lining as a unit. This construction is shown in Fig. 55 1 in which the shell is divided as indicated at 30.

While we have herein shown and described the best embodiment of the invention 60 of which we are at present aware, it will be appreciated that this embodiment may be modified as above suggested and in many other particulars without departing from the spirit or scope of this invention.

Having thus described our invention what 65 we desire to claim as new is:

1. A furnace of the character described, comprising a lower section, a hearth supported in said section, said section having a combustion chamber therein below said 70 hearth, and an arch cooperating with said section to enclose the hearth and mounted for movement relative to said section to open the side of the furnace for the lateral introduction or withdrawal of the charge. 75

2. A furnace of the character described, comprising upper and lower furnace sections, a hearth supported in said lower section, the lower section having a combustion chamber therein below said hearth, means supporting the upper section for movement relative to the lower section to open the side of the furnace for the lateral introduction or withdrawal of the charge, and an observation opening in said upper section. 80

3. A furnace of the character described, comprising a lower section, a hearth mounted therein, an arch shaped upper section pivotally mounted so that it may be raised or lowered to open or close said furnace. 85

4. A furnace of the character described, comprising a stationary lower section, a hearth mounted horizontally in said section and having its upper surface substantially flush with the front edge of said section, and an arch pivoted at the back of the furnace whereby it may be raised or lowered to open or close said furnace. 90

5. A furnace of the character described, comprising a substantially horizontal hearth, 100 a lower furnace section in which said hearth is mounted, said section having a combustion chamber therein below said hearth, flues leading from the opposite ends of the furnace, an arch having a pivotal connection with said lower section at the rear thereof, and means for raising and lowering the front of said arch to open or close the furnace. 105

6. A furnace of the character described, comprising a substantially horizontal hearth, 110 a lower furnace section in which said hearth is mounted, said section having a combustion chamber therein below said hearth, pipe connections at the front of said furnace for conducting a fuel mixture into said chamber, 115 flues leading from the opposite ends of the furnace, an arch having a pivotal connection with said lower section at the back thereof, means for raising and lowering said arch to open or close the furnace, said arch having observation openings therein, and means for normally closing said openings. 120

7. A furnace of substantially cylindrical form divided into upper and lower semi-cylindrical sections, a horizontal hearth supported in the lower section, said lower section having a combustion chamber therein below said hearth, means supporting said 125

upper section for pivotal movement on a horizontal axis located at the back of the furnace, and means for raising and lowering the front of said upper section to open or 5 close the furnace.

8. A furnace of the character described, comprising a substantially horizontal hearth and upper and lower furnace sections en-

closing said hearth, each of said sections comprising a metal shell with a lining of refractory material, and said shells being divided transversely into sections. 10

In testimony whereof we have signed our names to this specification.

S. THEODORE BITTENBENDER.
JOHN G. ALLAN.
